Primary Examiner—Stella Reid

[57] CLAIM

The ornamental design for an endotracheal tube stabilizer, as shown and described.

DESCRIPTION

FIG. 1 is a front elevational view of an endotracheal tube stabilizer, showing my new design;
FIG. 2 is a rear elevational view thereof;
FIG. 3 is a right side elevational view thereof;
FIG. 4 is a left side elevational view thereof;
FIG. 5 is a top plan view thereof;
FIG. 6 is a bottom plan view thereof;
FIG. 7 is an enlarged fragmentary view of the adhesive and peel away section of the endotracheal tube stabilizer; and,
FIG. 8 is a front perspective view thereof.
